UNITED STATES PATENT OFFICE

164,994

TENT PIN

Allan N. Johannesen, Jeffersonville, Ind.

Application October 4, 1949, Serial No. 5,297

Term of patent 3½ years

(Cl. D88—3)

To all whom it may concern:

Be it known that I, Allan N. Johannesen, a citizen of the United States of America, residing at rural rte. #1, Terrace Heights, Jeffersonville, in the county of Clark and State of Indiana, have invented a new, original, and ornamental Design for a Tent Pin, of which the following is a specification, reference being had to the accompanying drawings, forming a part thereof.

I claim:

The ornamental design for a tent pin, as shown.

ALLAN N. JOHANNESEN.
